UNITED STATES PATENT OFFICE.

CYRUS L. SULZBERGER, OF NEW YORK, N. Y.

DESIGN FOR SKIRT-BINDING.

SPECIFICATION forming part of Design No. 29,778, dated December 6, 1898.

Application filed November 10, 1898. Serial No. 696,086. Term of patent 14 years.

To all whom it may concern:—

Be it known that I, CYRUS L. SULZBERGER, of the city of New York, borough of Manhattan, in the county and State of New York, have 5 invented and produced a new and original Design for a Skirt-Binding, of which the following is a full, clear, and exact description.

Reference is to be had to the accompanying drawings, forming a part of this specification, 10 in which similar characters of reference indicate corresponding parts in all the views.

Figure 1 is a face view of a skirt-binding, showing my design. Fig. 2 is a rear face view of the same, and Fig. 3 is an edge view of the 15 same.

The design in its entirety consists of a body A, a depending brush B, abutting with its head B' against the lower edge of the rear-

wardly doubled-up lower portion A' of the body, as appears in the edge view, Fig. 3, and 20 stitching C appears between the doubled-up portion and the head, said stitching covering the doubled-up portion at the reverse of the binding and appearing as a longitudinal ridge having a corded effect. 25

The leading feature of the design consists of the body A, the depending brush B, and the stitching appearing as a corded ridge between the brush and body.

I claim—

The design for a skirt-binding, as herein shown and described.

CYRUS L. SULZBERGER.
